ing beneath the polishing runners, thus insuring a lower temperature in the plate 15 than is the case with the construction of Figs. 1 to 5, in which there is no circulation. This constant circulation is provided by means of a pump 28 which is carried on the bottom of the table and driven from the electric motor 29. This pump has an intake 30 projecting into a trough 31, which extends the length of the polishing system. The water taken up by the pump is discharged through the pipe 32 to the space 17 and is continuously exhausted from such space through a pipe 33 which discharges into a trough 34 which also extends the length of the polishing system. In this manner a continuous flow of water through the space 17 is provided during the period in which the glass is being polished. In order to provide for the automatic stopping and starting of the motor 29, the power is supplied from a pair of rails 35 supplied with current from the leads 36. These rails begin at the point of travel of the table at which it is desired that the motor should start and terminate at the point where the table passes the last polishing runner, so that the automatic stopping and starting of the pumping action is provided for, contact brushes carried on the base of the motor

engaging the rails, as shown. In order to insure that the space 17 shall be completely filled with water and, therefore, contact with the lower surface of the plate 15 throughout its area, the outlet pipe 33 leads up to a point above the lower level of the plate 15, as indicated in Fig. 7, a suitable recess 37 being provided for this purpose. 5

What we claim is:

A plate glass grinding and polishing table mounted for movement along a track and comprising a metal body portion having a flat rectangular upper face, a false top for the table comprising a metal plate spaced above said face in parallel therewith, positive spacing and clamping means distributed over the area of said face for maintaining the false top in fixed relation to said face throughout its area, fluid supply means extending along the line of travel of the table, a motor driven pump carried by the table, connections from said pump to the fluid supply means and from the pump to the space between said face and said top, a discharge outlet from said space, and means controlled by the movement of the table for starting and stopping the operation of the pump. 10 15 20 25
